CLEMENT A. HARDY, OF CHICAGO, ILLINOIS, ASSIGNOR TO WHITING CORPORATION, OF HARVEY, ILLINOIS, A CORPORATION OF ILLINOIS

SUPPORT FOR CUPOLA BUCKETS

Application filed May 26, 1928. Serial No. 280,743.

My invention relates to supports for cupola buckets.

One of the objects of the invention is to provide a simple, practical and advantageous support in a cupola for a charging bucket to support the bucket while discharging.

Another object of the invention is to provide a cupola bucket support which will permit the bucket to be introduced into the cupola and unloaded by the use of a suitable charging mechanism.

Another object of the invention is to make possible the introduction and unloading of the bucket in the cupola by means of a single supporting cable without the use of any unlocking or unlatching arrangements.

Another object of the invention is to secure simplicity of construction and reduce the cost of manufacture and installation.

20 In the accompany drawings:

Fig. 1 is a view partly in elevation and partly in vertical section of a portion of a cupola and a cupola bucket and bucket support involving my invention, the bucket being shown in an open condition;

Fig. 2 is a view similar to Fig. 1 with the bucket shown in a closed condition;

Fig. 3 is a cross section taken on line 3—3 in Fig. 1 but with the bucket removed;

30 Figs. 4 and 5 are, respectively, a cross section and the vertical elevation of a modified form of cupola support and a portion of the cupola;

Figs. 6 and 7 are similar views of a further modification; and

Fig. 8 is a view similar to Fig. 4 of a further modification.

Referring to Figs. 1, 2 and 3 of the drawings, I show a cupola 1 having a portion 2 provided with a side opening 3 which may be used for the introduction and withdrawal of the cupola bucket and carrying or charging device, and also having a lower portion 3 containing the cupola charge 4, of coke, iron and flux.

As an illustration of a charging mechanism, I show the end portion of a beam 5 which is understood to be carried and moved by suitable mechanism such, for example, as is well known in the art.

The beam 5 is provided with a pulley 6 over which is extended a cable 7 the end of which is provided with a hook 8 adapted to engage and support the attaching member of a cupola bucket.

As an illustration of a cupola bucket I show a bucket 9 which may be of substantially cylindric shape and which is provided with a conical separable bottom 10. This bottom 10 is provided with a flange 11 adapted to fit against the lower edge of the bucket 9 so that in its closed condition the flange 11 will fit against the underside of the bucket body proper, as shown in Fig. 2. While in its open condition the bottom 10 will be lowered or separated from the body of the bucket proper 9, as shown in Fig. 1.

The bucket bottom 10 is provided with an upwardly extending member or element preferably in the form of a rod or beam 12 whose upper end may be provided with a ring 13 adapted to engage the hook 8 at the end of chain 7. Thus the bucket may be held in suspension in a closed condition, as shown in Fig. 2, or raised or lowered, or moved in any desired direction in that condition by means of the cable 7 having its hook 8 engaged with the ring 13.

I further show a support for the bucket which will permit the bucket to be introduced into the cupola but which will engage the bucket body portion proper and hold it in position while at the same time permitting the bottom of the bucket to be lowered so as to open the bucket and discharge its contents. This bucket support could have various different forms and constructions. In this application I show four different forms or constructions, but it will be understood that others could be devised within the spirit of the invention.

One of the forms shown is illustrated in Figs. 1, 2 and 3. This comprises a supporting member 14 which may conveniently be in the form of a wish-bone, having two side limbs or members 15, 15 connected to one another and to a third member 16. The side members 15 are preferably provided with slightly inclined end portions 17 and these are fitted in sockets or holders 18 at the oppo-

site sides of the cupola mouth or opening 3, so that the bucket may be moved bodily into the cupola through the opening 3 and between the side members 15. The other member 16 is in the rear or back of the cupola, opposite the mouth 3 and passes through a small or supplemental opening 18 in the cupola, resting on the ledge or shoulder at the bottom of said opening, as shown in Fig. 1. The member 16 is preferably provided with a downwardly extending shoulder 19 to engage the back of the cupola, or a plate 20 thereon, so as to prevent forward or outward movement of the member 14. Aside from this engagement of shoulders 19 and 20 the member 14 is preferably loose in the cupola, so that if desired it may be bodily removed from time to time for cleaning or renewal purposes or replacement.

The members 15 are at such distance apart as to permit the bucket body 9 to pass readily between them so that the bucket may be moved readily into proper position in the cupola. But the upper portion of bucket body 9 is provided with an outwardly projecting member or element such as the flange 21, which is adapted to engage members 15 when the bucket is lowered. Thus the bucket may be moved into the cupola by means of the charging mechanism, the bucket being in a closed condition, as shown in Fig. 2, and containing a suitable charge such, for example, as coke or iron, and then the bucket may be lowered so that its flange 21 will engage the side members 15 of the support 14 and so that further lowering by the charging mechanism will permit the bottom 10 only to descend, thereby discharging the contents of the bucket into the cupola, as desired. After discharge the charging mechanism may be operated so as to first act upon the cable 7 and cause the bottom 10 to rise and close the bucket and then the beam 5 will be moved so as to move the bucket away from the support 14 and out of the cupola.

In the arrangement shown in Figs. 4 and 5, the support 14^a is provided with side members 23, 23 substantially parallel with one another and provided with outwardly inclined ends 24 similarly to the ends of the support 14 and these side members 23 are preferably extended back through openings 25, 25 in the cupola and connected with one another by a straight cross member 26. The operation of the bucket in connection with this support 14^a is substantially the same as it is in connection with the support 14.

In the arrangement shown in Figs. 6 and 7 a support 14^b is arranged within the cupola and provided with a plurality of more or less radially extending members 28, 28 whose inner ends are adapted to engage the holding shoulder or projection, such as flange 21 on the bucket body and thereby permit the operation of the device, as previously described.

The arrangement shown in Fig. 8 comprises side members 23^a, which may be independent of one another and may be supported at their opposite ends in supports 18 on the cupola walls. By this construction a cupola having a rear or back mouth or opening, as well as a front mouth or opening, may be provided with a bucket support as well as cupolas provided with front openings only.

Thus it will be seen that the mechanism is simple, practical and advantageous and that the bucket may be readily introduced into the cupola and unloaded and then removed in an empty condition in a very quick and expeditious manner and that this may be accomplished simply by the single bucket carrying cable or element 7 of the charging mechanism, there being no latching or locking arrangements requiring a separate and additional cable or elements for operation. It will also be seen that the entire mechanism is inexpensive and may be easily and cheaply manufactured and installed.

It will be understood that changes and modifications may be made without departing from the spirit of the invention.

What I claim is:

1. A support for a cupola bucket having side supporting members with diverging portions adapted to permit the ready entrance between them of the body of the bucket and also adapted to engage horizontal side projecting or shoulder portions on the bucket body for supporting said body.

2. A support for a cupola bucket having side supporting portions adapted to engage shoulder portions on the bucket body and also having a diverging front opening to permit the free movement of the bucket body into the space between said side supporting portions.

3. A support for a cupola bucket having side members spaced apart to permit the movement of the bucket body between them and adapted to engage shoulder portions on the bucket body, and a cross connection between said side members to serve as a stop for limiting the inward movement of the bucket.

4. The combination with a cupola, of a bucket support comprising side members on the opposite sides of the cupola opening for engaging and supporting the bucket body, and a rear member for limiting the inward movement of the bucket.

5. The combination with a cupola bucket, of a support therefor, said support having a portion thereof arranged to encompass the bucket and other portions extending from the encompassing portion arranged to rest on and be supported by a cupola wall.

6. The combination with a cupola bucket, of a support therefor, said support having a portion thereof arranged to encompass the bucket and other portions extending from the encompassing portion arranged to rest on and be supported by a cupola wall, the said bucket

having a projection extending therefrom arranged to engage the encompassing portion of the said support for sustaining the said bucket.

5 7. The combination with a cupola bucket, of a support therefor, said support having a portion thereof arranged to encompass the bucket and support same and other portions of the said support arranged to lead the bucket for centering same with respect to the said encompassing portion of the said support.

10 8. The combination with a cupola bucket, of a support therefor, said support having a portion thereof arranged to encompass the bucket and other portions extending from the encompassing portion arranged to rest on and be supported by a cupola wall, said other extending portions having means for holding 20 the support assembly in position.

15 9. The combination with a cupola and a cupola bucket, of a support therefor, said support having a portion thereof arranged to encompass the bucket and other portions 25 extending from the encompassing portion arranged to rest on and be supported by a cupola wall, said other extending portions having means for holding the support assembly in position, said means including a hook-like projection for engaging the wall of the 30 cupola.

35 10. In combination, a cupola, a cupola-bucket-support therein, projections extending from the said support for engaging the cupola wall, openings in the cupola wall for receiving said projections of said support, and means on the said projections for retaining the said support in position in said cupola.

40 11. The combination with a cupola and a cupola bucket of a support having guiding and supporting portions arranged for receiving and centering the said bucket upon its entrance to the cupola, and shoulder portions on the bucket extending from the sides thereof for engaging the said support after the placement of the said bucket in the said support.

45 12. A support for a cupola bucket, said support having guiding and supporting portions, said guiding portions being outspread to receive a bucket therebetween; horizontal projecting portions on the sides of the bucket to engage the supporting portions of said support.

55 13. A cupola bucket support comprising side members adapted to engage and support a cupola bucket and provided with portions adapted to fit removably in the walls of a cupola so as to permit the support as a unit 60 to be inserted into and removed from the cupola.

65 14. A cupola bucket support comprising side members for engaging and supporting a cupola bucket, said side members being spaced apart at one end to permit the entrance of the

bucket and being connected together at the other end to hold them together as a unitary structure, the spaced apart ends being adapted to rest removably upon shoulders on the cupola wall and the other end of the support being also removably mounted on said wall. 70

15. A cupola bucket support comprising a portion adapted to engage and be supported by the cupola wall and having inwardly extending members adapted to engage and support the cupola bucket. 75

16. A cupola bucket support comprising a portion adapted to engage and be supported by the cupola wall and having inwardly extending prongs adapted to engage and support the cupola bucket. 80

In witness whereof, I hereunto subscribe my name this 28th day of April, A. D. 1928.

CLEMENT A. HARDY.
